UNITED STATES PATENT OFFICE.

THOMAS HOWARD WATTS, OF ALTOONA, PENNSYLVANIA.

GONDOLA CAR.

1,178,462.

Specification of Letters Patent. Patented Apr. 4, 1916.

Application filed May 28, 1915. Serial No. 30,925.

To all whom it may concern:

Be it known that I, THOMAS H. WATTS, a citizen of the United States, and a resident of Altoona, in the county of Blair and State 5 of Pennsylvania, have invented an Improvement in Gondola Cars, of which the following is a specification.

The present invention relates to gondola cars, and more particularly to a drop door 10 operating and locking mechanism.

The primary object of the invention is to provide an apparatus of this character which embodies a novel construction for retaining the pivoted doors of the car in closed 15 position and which, when operated, will greatly facilitate the opening and closing of said doors, the mechanism for such operation being so arranged that substantially a third of a complete revolution of the operating crank is all that is required to open or 20 close the doors.

Another object is the provision of mechanism for effectively accomplishing the above results and which is simple in construction, 25 inexpensive to manufacture, and which may be readily applied to gondola cars now commonly used.

The inventive idea involved is capable of receiving a variety of mechanical expressions, one of which, for the purpose of illustrating the invention, is shown in the accompanying drawings, in which—

Figure 1 is a top plan view of the mechanism for operating the doors of the car, 30 the cover for said mechanism being removed. Fig. 2 is a longitudinal section on the line 2—2 of Fig. 1, showing the mechanism in position for retaining the doors closed. Fig. 3 is a view similar to Fig. 2 35 showing the mechanism in the position assumed when the doors are open. Fig. 4 is a longitudinal section taken on a line outside of the sill member and looking in the direction thereof. Fig. 5 is a transverse 40 section with the mechanism in end elevation, and Fig. 6 is a detail view of the door supporting members used in connection with the invention.

Referring more particularly to the accompanying drawings in which like reference characters indicate similar parts, the 50 numeral 10 indicates a pair of longitudinally extending parallel girders usually arranged centrally of the car and provided 55 with a cover 11 said girders and cover form-

ing what is commonly known as the sills. The car frame has pivoted thereto on the outer sides of the girders 10 the doors 12 which open downwardly in opposite directions and have their free ends meeting when in closed position, as clearly shown in Fig. 4. The corresponding doors 12 which are arranged on opposite sides of the sills and which open in the same direction are connected by suitable arched door braces 13, 60 Fig. 5, which cause the doors to move in unison. The mechanism which comprises the essential feature of this invention includes a pair of oppositely disposed brackets 14 secured to the inner adjacent faces of the girders 10 and provided with slots 15 for the reception of the ends of a hub 17 adapted to rotate between said brackets 14. A bell crank lever 18 is preferably made integral with the hub 17 and has pivotally 65 connected to one of its arms one end of a link 19 the other end of which is pivoted at 20 to the adjacent end of a similar link 21, said adjacent ends being provided with lugs 22 adapted for engagement with each other 70 whereby said links are normally retained in substantial alinement and prevented from further movement about the pivot 20 in one direction. An operating shaft 23 is transversely mounted in the sills and has one end 75 extending beyond the side thereof for the reception of a handle, not shown, which is adapted to rotate said shaft for causing the crank arm 24, which is pivoted at 25 to the link 21, to move said links to the position 80 shown in Fig. 3.

Oppositely disposed levers 26, which form supporting members for the doors 12, are pivoted at 27 to the bell crank lever 18 and at 28 to said doors 12. Each of the levers 26 is provided at its upper end with a substantially V-shaped portion 29 and intermediate the ends thereof the same is provided with a curved portion 30 which forms a shoulder 31 which is adapted to engage the hub 17 so that when the doors 12 are in closed position said shoulder is so located that the doors connected to the lever will be supported and the line of stress will be in a plane passing vertically through the center 95 of the hub. Thus the greater the weight on the doors the more tendency there will be for the shoulders 31 to bind against said hub and therefore the doors will be effectively retained in a closed position. The 100 105 110

lower ends 32 of the levers 26 extend in opposite directions and cross each other as shown in Figs. 2 and 6.

In practice, the handle of the shaft 23 is turned so as to move the crank arm 24 in the direction of the arrow, as shown in Fig. 2, thus moving the links 19 and 21 to the left and swinging the bell crank lever 18 about its pivot, which is the hub 17. This movement will disengage the shoulders 31 of the levers 26 from said hub and permit the parts to move to the position shown in Fig. 3, when the adjacent pivoted ends of the links 19 and 21 will rest upon said hub. It will be apparent from an inspection of the drawings that owing to the particular arrangement and construction of parts it will only be necessary to give the crank arm 24 approximately a third of a revolution in order to permit the parts to move to a position where the doors 12 will be entirely open. When it is desired to close the doors, the operating handle is rotated in an opposite direction from that just described which will cause the parts to move in the direction of the arrows shown in Fig. 3.

I claim:—

1. In a gondola car, the combination of sills, doors arranged on each side thereof, a rotatable supporting member mounted in said sills, connections between said doors and supporting member adapted to be supported on the latter when the doors are closed, and means including a crank arm adapted to be given approximately a third of a revolution whereby to disengage said connections from said supporting member to open said doors.

2. In a gondola car, the combination of sills, doors arranged on each side thereof, a rotatable member carried by said sills, substantially Z-shaped supporting levers connected to said doors and having intermediate portions adapted for supporting said levers on said rotatable member to re-

tain said doors in closed position, and means including an oscillatory element for disengaging said supporting members from said rotatable member to open said doors.

3. In a gondola car, the combination of sills, doors arranged on each side thereof, a rotatable member carried by said sills, supporting members connected to said rotatable member and said doors and having curved portions adapted for engagement with said rotatable member to retain said doors in closed position, pivoted link connections for disengaging said supporting members from said rotatable member to open said doors, and means associated with said link connections for retaining the same substantially in alignment when said doors are not being opened.

4. In a gondola car, the combination of sills, doors arranged on each side thereof, a rotatable hub mounted transversely of said sills, a bell crank lever carried by said hub, supporting levers connected to said bell crank lever and to said doors, each of said levers having a curved portion adapted to engage said hub for supporting said doors in a closed position, and means connected to said bell crank lever for rotating said hub to disengage said supporting levers therefrom to open said door.

5. In a gondola car, the combination of sills, doors arranged on each side thereof, a rotatable hub mounted transversely of said sills, a bell crank lever carried by said hub, supporting levers connected to said bell crank lever and to said doors, each of said levers having a curved portion adapted to engage said hub for supporting said doors in a closed position, and link connections pivoted to said bell crank lever and adapted to be operated to disengage said supporting levers from said hub whereby said doors are opened.

THOMAS HOWARD WATTS.
